HENRY F. SCHMIDT, OF PITTSBURGH, PENNSYLVANIA, ASSIGNOR TO WESTINGHOUSE ELECTRIC AND MANUFACTURING COMPANY, A CORPORATION OF PENNSYLVANIA.

BLADE-MOUNTING.

1,345,642.

Specification of Letters Patent.

Patented July 6, 1920.

Original application filed March 31, 1917, Serial No. 158,977. Divided and this application filed June 22, 1918, Serial No. 241,433.

To all whom it may concern:

Be it known that I, HENRY F. SCHMIDT, a citizen of the United States, and a resident of Pittsburgh, in the county of Allegheny and State of Pennsylvania, have made a new and useful Invention in Blade-Mounting, which is a division of an application for patent, filed March 31, 1917, Serial No. 158,977, of which the following is a specification.

This invention relates to blade mounting and particularly to that form of blade mounting used in fluid turbines and the like, and has for an object to produce a new and improved blade mounting which is especially adapted to be employed in attaching blades to moving blade carrying elements.

A further object is to produce a riveted blade mounting in which means are provided to counteract eccentric loading of the parts forming the joint.

These and other objects are attained by means of the blade mounting described herein and illustrated in the accompanying drawing, wherein—

The figure is a diagrammatic sectional view of a blade mounting embodying the invention.

Turbine blades have frequently been mounted by inserting their shanks in a groove in the blade carrying element and by then securing each blade shank in place with one or more locking members such as rivets. The ordinary construction consists in a single groove in the blade carrying element and a single tongue on the blade shank so that the rivets are in double shear. The result would be the same if the blade shank straddled a single tongue on the blade carrying element. In either construction, the size of the rivet or rivets is limited by the pitch of the blades and consequently by the amount of material which may be left in the shank. The number of rivets of a reasonable size is limited for the same reason. As the number and size of the rivets are limited, the strength and efficiency of the joint are also limited in the single tongue and groove construction.

In my invention I increase the efficiency and strength of the blade mounting by increasing the number of times some of the locking members or rivets are in shear. Although the number and size of the mem-

bers or rivets are limited as before, the strength of the joint is greatly increased by improving the efficiency of the joint. In carrying out my invention, I preferably provide a multiple tongue and groove joint between the blade shank and the blade carrying element, which is so formed as to throw all or a part of the locking members or rivets in more than double shear and to thereby increase the efficiency and hence the strength of the joint. Obviously this may be done without increasing the weight of the joint, and at substantially the same cost as the cost of the old construction, by increasing the number of tongues in the joint and by decreasing their thickness. It is evident that the efficiency of the joint is further increased by the greatly increased amount of surface, due to the multiple tongue construction, held in frictional engagement by the rivets.

In the figure I have illustrated a portion of a blade carrying element 5 and a portion of a blade 6, which is mounted on the blade carrying element 5. The shank of the blade 6 is shown as provided with three tongues 7, 8 and 9, which fit into grooves in the blade carrying element 5 and coöperate with two tongues 10 and 11, formed on the blade carrying element 5. The central tongue 8 of the blade shank is shown longer than the two side tongues 7 and 9, so that an inner locking member or rivet 12 passes through only the central tongue 8 and is therefore only in double shear. An outer locking member or rivet 13 passes through the tongues 7, 10, 11 and 9 and is therefore in quadruple shear.

In order for the blade to tear away from the blade carrying element 5, it would be necessary for it to shear off six rivet sections. If the multiple tongue construction were not provided, the total number of rivet sections to be sheared off would be only four, consequently the strength of the joint has been increased by a shear area equal to twice the section of one of the rivets. This is accomplished without increasing the weight or cost of the joint, consequently the efficiency of the joint is materially improved. This mounting is simple, compact, and makes possible a smooth continuous joint, due to the fit of the tongues 7 and 9 against the blade carrying element 5 as shown.

In order to counteract bending stresses due to eccentric loading of the tongues 7 and 9, the free ends of such tongues are provided with extensions 14 and 15, adapted to project into and interlock with grooves 16 and 17 formed in the carrying element 5. This interlocking construction of the outer tongues 7 and 9 constitutes the essential difference between the construction disclosed 5 in the above mentioned application and the present construction. The outer flanges or tongues are reinforced against spreading without the use of additional rivets and consequently the construction is simple and 10 rigid.

While I have described and illustrated but one embodiment of my invention, it will be apparent to those skilled in the art that various modifications, changes, additions and 15 omissions may be made in the apparatus described and illustrated without departing from the spirit and scope of the invention, as set forth by the appended claims.

What I claim is:

25. 1. A blade mounting comprising a blade shank provided with at least three tongues

adapted to interleave with at least two tongues provided upon a blade carrying element, the free ends of the outer tongues having interlocking engagement with the adjacent portion of the inner tongues for preventing lateral displacement of the outer tongues, and means for preventing separation of the joint in a longitudinal direction. 30

2. A blade mounting comprising a shank 35 element forming a multiple tongue groove joint with a blade carrying element, one of the said elements being provided with at least three tongues adapted to interleave with at least two tongues provided upon the other element, the free ends of the outer tongues having interlocking engagement with the adjacent portion of the inner tongues for preventing lateral displacement of the outer tongues, and means for preventing 40 longitudinal separation of the joint. 45

In testimony whereof I have hereunto subscribed my name this 20th day of June, 1918.

HENRY F. SCHMIDT.

Witness:

C. W. McGHEE.
